United States Patent Office

Des. 182,887
Patented May 27, 1958

182,887

WASHING MACHINE OR SIMILAR ARTICLE

Montgomery Ferar, Huntington Woods, Mich., assignor to Whirlpool Corporation, a corporation of Delaware

Application September 6, 1956, Serial No. 42,844

Term of patent 14 years

(Cl. D49—1)

FIG. 2

The dominant features of the design are shown in full lines.

I claim:

The ornamental design for a washing machine, or similar article, as shown and described.
